UNITED STATES PATENT OFFICE.

STEPHEN T. SHORTESS, OF VINTON, IOWA.

DEVICE FOR OVERCOMING DEAD-CENTERS.

SPECIFICATION forming part of Letters Patent No. 331,914, dated December 8, 1885.

Application filed September 26, 1885. Serial No. 178,290. (No model.)

To all whom it may concern:

Be it known that I, STEPHEN T. SHORTESS, a citizen of the United States, residing at Vinton, in the county of Benton and State of Iowa, 5 have invented certain new and useful Improvements in Devices for Overcoming Dead-Centers; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 This invention relates to means for overcoming dead-centers in machinery driven by a rod or pitman; and it particularly relates to that class in which the ordinary pitman is replaced by one of sufficient elasticity, and is 20 so disposed between the crank and treadle, or its equivalent, that the crank at no time will be on a dead-center, either while in motion or at rest. Heretofore these elastic pitmen have been pivotally attached to the crank and rigidly attached to the treadle. Thus the angle 25 between the pitman and treadle remained relatively fixed, and as the efficiency of the pitman to carry the crank past its dead-points depends upon the elasticity of the pitman, and 30 this in turn upon the variation of said angle, prior devices were found objectionable, as they failed to provide any means for varying this angle; hence the object of this invention is to provide means for varying the angle between the pitman and treadle, or its equivalent, by shifting the position of the pitman to 35 and from the axis about which the treadle vibrates; and to this end it consists in the details of construction, as more fully hereinafter 40 set forth and specifically claimed.

In the accompanying drawings, Figure 1 is 45 a side elevation of a portion of a stand provided with a fly-wheel and treadle, the latter being shown in section, the parts being connected according to my improvement. Fig. 2 is a section on the line X-X of Fig. 1, the stand being removed, and showing the preferred means of attachment between the treadle and the elastic rod. Fig. 3 is a rear edge view 50 of a modified form. Fig. 4 is a detail perspec-

tive view of the clip, showing the same in position upon a portion of the treadle-shaft with the elastic rod attached thereto.

The frame A, which may be of any well-known construction, is simply shown as a 55 means of support for the fly-wheel B, the treadle C, and the shaft D. The rod E, which is made of a suitable material possessing elastic properties, is connected to the treadle at its lower end in such a manner that if the other end of 60 the rod were free it would, on operating the treadle, describe an arc of a circle of which the treadle-shaft would be the center—that is to say, the connection between the rod and the treadle should be relatively fixed and not a 65 pivotal one. The free end of the rod should be pivotally connected with the crank G on the shaft carrying the fly-wheel.

In disposing the parts it is best to have the rod E of such length and fastened to treadle 70 at such an angle that the crank and treadle will normally rest in position off their dead-points.

By my invention the rod can be readily attached and detached, and the point of attachment between the rod and the treadle may be adjusted nearer to or farther from the treadle-shaft, to regulate the tension or elastic force of the rod. The elastic rod E is bent near its lower end, and said portion e is passed through 75 80 an eye or keeper, H, on the side of the treadle, and thence through the flanges i of a clip, I, surrounding the treadle-shaft. The end of the bent part e is threaded for a short distance, and nuts n, mounted thereon one on either 85 side of the flanges of the clip, serve to adjust the point of contact between the bent part of the rod and the eye attached to the treadle, besides causing the clip to bind around the shaft about which the treadle oscillates. 90

From the foregoing it will be seen that the angle between the rod and its bent portion or treadle is only varied when the treadle is operated, and it is this variation in said angle which causes a manifest lateral straining of 95 the rod, the rebound or recoil of which is utilized to carry the crank past its dead-point.

The dotted lines of Fig. 1 show the rod in position and just in the act of passing the dead-point, the rod being strained inward, as indi- 100

cated by the arrow. The full lines show the portion of the rod after having passed the upper dead-point, the arrow 2 indicating the direction of strain upon the rod when the latter is carried past its lower dead-point.

As the working of the device depends upon the elasticity of the rod and the rigidness of its connection with the treadle or the shaft, in order that the operation of the treadle may cause a lateral straining of the rod, it has been found by practical demonstration to be immaterial whether the rod is used singly, as shown in Fig. 1, or in connection with an ordinary pitman, as indicated in Figs. 2 and 3. It is manifest that a number of such rods, as E, may be employed, if found necessary, and also that the same may be attached at their lower ends to the opposite end of the treadles and on the opposite side of the support thereof, provided that they are attached to the same side of treadle as the pitman. Changing sides reverses the motion, and for this purpose the elastic pitman may be put on the side opposite to the one shown in drawings.

Having thus described my invention, what I claim, and desire to secure by Letters Patent, is—

The combination, with the crank and a treadle loosely mounted on a shaft, of an elastic rod journaled at one end to the crank, the other end bent and passed through a keeper near the forward end of the treadle, the extreme end of the bent portion being threaded, a flanged clip mounted on the treadle-shaft and secured thereto by the threaded end of said rod passing through its flanges, and nuts, one on either side of the flanges, whereby the point of contact between the keeper and rod may be relatively changed or adjusted, substantially as and for the purpose set forth.

In testimony whereof I affix my signature in presence of two witnesses.

STEPHEN T. SHORTESS.
